DESIGN FOR A SHOWCASE

Gordon S. Cushman, New York, N. Y., assignor to Cushman's Sons, Inc., New York, N. Y., a corporation of New York

Application October 21, 1946, Serial No. 134,129
Term of patent 14 years

(Cl. D80—11)

To all whom it may concern:

Be it known that I, Gordon S. Cushman, a citizen of the United States, residing at New York, in the county of New York and State of New York, have invented a new, original, and ornamental Design for a Showcase, of which the following is a specification, reference being had to the accompanying drawing, forming part thereof.

Fig. 1 is a perspective view of a show case showing my new design;

Fig. 2 is a side elevation of the same; and

Fig. 3 is an end elevation of one-half of the same.

I claim:

The ornamental design for a showcase, substantially as shown.

GORDON S. CUSHMAN.
